DESIGN FOR A ROSARY PLAQUE

Raymond F. Brennan, Attleboro, Mass.

Application November 13, 1942, Serial No. 108,760

Term of patent 14 years

To all whom it may concern:

Be it known that I, Raymond F. Brennan, a citizen of the United States, residing at Attleboro, in the county of Bristol and State of Massachusetts, have invented a new, original, and ornamental Design for a Rosary Plaque, of which the following is a specification, reference being had to the accompanying drawings, forming part thereof.

Fig. 1 is a front elevational view of the plaque, showing my new design;

Fig. 2 is a rear elevational view of the plaque,
Fig. 3 is a vertical sectional view through
the plaque taken substantially along the lines
3—3 of Fig. 1 and,

Fig. 4 is a transverse sectional view through
the plaque, taken substantially along the lines
4—4 of Fig. 2.

I claim:

The ornamental design for a rosary plaque,
substantially as shown.

RAYMOND F. BRENNAN.
